Primary Examiner — Melanie Pellegrini(74) *Attorney, Agent, or Firm* — QuickPatents, LLC;
Kevin Prince(57) **CLAIM**

I claim the ornamental design for a ring, as shown and described.

DESCRIPTION

FIG. 1 is a bottom perspective view of a ring, showing my new design;

FIG. 2 is a front elevational view thereof, the rear elevational view being a mirror image thereof;

FIG. 3 is a left-side elevational view thereof, the right-side elevational view being a mirror image thereof; and,
FIG. 4 is a bottom plan view thereof.

The broken lines showing a gem in FIG. 1 depict environmental matter and form no part of the claimed design. The remaining broken lines represent a boundary of the claimed design. The top plan view is understood to form no part of the claimed design.
